Boyd A. Wise, Donald E. Cooper and Robert L. Thompson, Columbus, Ohio, assignors, by mesne assignments, to Drilling Research, Inc., Houston, Tex., a corporation of Delaware

Application April 22, 1953, Serial No. 350,314

38 Claims. (Cl. 255—4.6)

This invention relates to systems and apparatus for drilling wells, particularly deep wells needed to penetrate oil deposits, and has for an object the attainment of the desired depth of the well at lower cost and in less time than has heretofore been deemed possible.

Considerable work has been done on various systems of drilling including the rotary system characterized by the rotation of a bit under static load for the penetration of sub-surface strata. Impact drilling has also been successfully employed which is characterized by the raising and lowering of the bit so that it may strike with considerable impact the strata to be penetrated. Such systems have also been particularly useful in hard rock formations.

It has also been proposed to drill wells with a combination of such systems where there is rotary motion of the bit, together with vibration at frequencies in the neighborhood of 60 cycles per second, the vibration being produced by rotation of eccentric weights included as a part of the drill string. It has also been proposed to utilize higher-frequency impact drilling, but in such systems, as has characterized many proposals in the past the horsepower available has been severely limited, so much so as to make such systems relatively ineffective.

For economic reasons, deep wells which may extend several miles underground are necessarily of small diameter, the size of the casing ranging from five inches to about fifteen inches, the more usual size being from six to ten inches. The severe limitations of hole size require a motor type particularly suited to the application, if adequate forces and power are to be produced.

Magnetostriuctive motors of a specialized type, embodying features of the present invention, meet these restrictions and limitations, and have been found especially well suited to the drilling of wells. The severity of the limitations imposed by the small size of the borehole is magnified as the speed of drilling increases. As the bit penetrates more rapidly, the removal of the chips or fragments of the strata progresses at higher rate and thus requires increased circulation of "mud," a term generally used to refer to the medium which carries away the chips or fragments of the strata. Thus, there must be built into the drilling column a flow passage for the circulation at reasonable pumping pressures of mud in sufficient volume for rapid and efficient removal of the chips to maintain the drill in contact with strata and in its forward progress unimpeded by any substantial depth of chips and fragments.

In carrying out the present invention in one form thereof, there is provided a vibratory transducer secured to the lower end of a drill string, the transducer including a passage therethrough which forms an extension of a mud passage of the drill string and which is connected to a corresponding mud passage in the drill bit. A driving connection is provided between the transducer and the drill bit. The transducer itself, in its preferred form, includes an elongated magnetostriuctive driving member cylindrical in shape and made up of a multiplicity of laminations, each being of great length and of substantial

width to provide the radial thickness of the transducer driving element. The laminations are rigidly bonded together with an adhesive and together form a cylindrical or tubular member having stiffness approaching that of a metal cylinder or columnar member of the same thickness and of the same length. The transducer is preferably quite long, in the neighborhood of twenty-five feet, corresponding with a half wave length for longitudinal vibration at an operating frequency of about 100 cycles per second.

Between inner and outer concentric legs of the driving element, there is disposed an energizing winding, preferably of one layer, and extending throughout the major portion of the length of the driving element. The winding may be energized with all the turns in series, or it may be subdivided into coils with the several coils connected in parallel. Upon energization of the winding, the magnetostriuctive driving element is effective to drive the bit toward and away from strata to be penetrated and to develop impact forces of great magnitude when operated at the frequency of mechanical resonance corresponding to an electrical driving power ranging upwardly from about 100 kilowatts, and in conjunction with applied static loads in the general range of those used in current rotary drilling practice, amounting to roughly 1000 lbs. to 5000 lbs. per inch of bit diameter.

In providing a well-drilling system of the character so far briefly described, many additional features of construction and further improved procedures or processes have been utilized, and these will be explained more fully in the following more detailed description in which there have been included many further objects and advantages of the invention. Accordingly, reference may now be had to the following description taken in conjunction with the accompanying drawings, in which:

Fig. 62 is an enlarged fractional view of Fig. 61.

As has already been explained, the present invention is concerned with systems of, and apparatus for, drilling deep holes. In Fig. 1, there is shown a bit 10 engaging subsurface strata 17 at the bottom of the drill hole. The strata will frequently consist of different types of rock. Before presenting a detailed description of particular methods, systems and structures embodying the present invention, there will first be developed many of the concepts underlying the present invention. These concepts have resulted from mathematical analyses based on simplified assumptions, and upon experimental work verified in a field embodiment. The end result to be achieved is maximum economy as regards cost of operation and also in terms of depth of well drilled in a given time.

The present invention is largely concerned with the manner in which the bit 10 is caused to penetrate subsurface strata. The amount of material fragmented from the strata when a single blow is struck by the bit on the strata depends upon the force of the blow, the strata environment, the physical properties of the strata materials, and the size and geometry of the bit used. By making simple assumptions as to the relationship between the amount of material removed and the variables mentioned above, and by also making simple assumptions as to the effect of the spacing or indexing distance between successive blows in removing the material between the successive areas of engagement of the work by the bit, it has been found possible to derive mathematical expressions relating the rate of penetration to the number of blows per second, the rate of rotation of the bit, the peak value of the force exerted by the bit on the rock, the diameter of the bit, and the number of cutting edges on the bit. The foregoing relationships have been verified by drilling tests in the laboratory and also by drilling in the field. With the use of such relationships, it has been found that at a constant rate of penetration the peak value of the force exerted by the bit on the rock and the power required to drive the bit 10 against the rock both vary inversely as the square root of the vibration frequency, the latter being defined as the number of blows per second of the bit against the rock. In accordance with the invention, the same rate of penetration is achieved at higher vibration frequencies with lower force levels. For example, with half the force level required at 80 cycles per second the same rate of penetration is obtained with a vibration frequency of 320 cycles per second.

One method of obtaining a series of impacts on rock at a high frequency, say 100 to 1000 vibrations per second and high as compared with frequencies obtainable with mechanical devices employing moving parts to develop drilling forces of needed magnitude, comprises the use of a rigid column 12 vibrating longitudinally at its resonant frequency and carrying the bit at one end thereof. The bit 10 executes a sinusoidal motion when free of the rock or strata 17. In drilling, the bit is maintained in close proximity to the rock to be penetrated by applying a static load. As the bit engages the strata 17, the motion of the bit is greatly diminished, resulting in an impulsive force of the bit 10 on the strata or rock to be penetrated. The peak value of this force and its duration will depend upon the amplitude and frequency of vibration of the bit, the static load, the type of strata being engaged, and the geometry and size of the bit used. As the static load is increased from zero, the peak value of the force exerted by the bit on the rock at first increases approximately proportionately to the applied static load. The fraction of the cycle that the bit maintains contact with the rock at first remains approximately constant at a value determined by the type of rock and size and type of bit. This fraction, expressed as a percentage, will be hereinafter referred to as the "on-time." As the static load is still further increased, the value of the peak force levels off. However, the on-time begins to increase until 100 percent on-time is reached. At a static load, just sufficient to produce 100 percent on-time, the peak value of the vibratory force is equal to the static load applied and consequently the resultant force during a cycle varies from a minimum value of zero to a maximum value double that of the static load. Since the magnitude of the peak force is an important variable in determining the rate of drilling, it is desirable to operate under such circumstances that this force will be maintained at a maximum value. At an on-time of about 75 percent, the peak force is high and from practical considerations approximates its maximum value which is attained at 100 percent on-time. This value does not increase upon application of a static load greater than is required to obtain 100 percent on-time. In fact, it has been found experimentally that if the static load greatly

exceeds the dynamic vibratory force, the mechanism of drilling is essentially the same as that obtained by conventional rotary means except that the presence of a component of dynamic force, then small as compared with the static load, actually decreases the rate of penetration somewhat in comparison with what would be achieved with the static load alone.

As already stated, the bit 10 is rotated during drilling. The retarding torque produced by contact of the bit upon the rock has been found experimentally to decrease rapidly as the on-time is decreased from 100 percent. From the point of view of bit wear, operation at shorter on-times is to be preferred. A compromise mode of operation between high rates of penetration and reduced bit wear lies between about 50 percent and about 75 percent on-time, the particular optimum value depending upon the type of rock and type of bit. For the harder rocks, on-times closer to 50 percent are to be preferred. For the softer rocks, operation in the neighborhood of 75 percent will be preferred.

There will now be described more in detail systems and apparatus embodying the present invention and the manner in which such an apparatus fulfills the requirements above discussed. The invention in Fig. 1 is shown applied to drilling systems having components well understood by those skilled in the art. The drill rig or system includes a derrick 1 having a cable supporting the drill string through a suitable pulley system, the pull on the cable being controlled by the drawworks 2. The drill string is rotated in conventional manner, as by a rotary table; which is diagrammatically indicated in Fig. 1 by gears 5 driven from a speed-changing mechanism 6 and a motor or prime mover 7. The driving gear rotates the drill string by means of a suitable drive connection between the gear and the drill string, the driving connection in practice generally including a straight-sided section of drill string sometimes referred to as the "Kelly" and a complementary opening in the table or driving gear.

Lengths of drill pipe are connected together to form the major portion 21 of the drill string. A drill collar 15 is secured to the lowermost joint of drill pipe. Threadedly connected to the lower end of collar 15 is the upper section of a mechanical vibration filter 20. The vibratory column including the transducer 12 is secured to the lower section of the filter 20, the bit 10 being rigidly connected to the lower end of the vibratory column.

Electrical power is supplied to a magnetostrictive type of transducer 12 from an alternating current generator 162 having a field winding 162a energized from an exciter 8, driven by an auxiliary power unit 8c whose field winding 8a is self-excited under the control of a rheostat 8b. The generator 162 is driven by a prime mover 175 which may be a diesel engine. Driven by prime mover 175a is a direct-current generator 168 having a self-excited field 168a, the energization of which is under the control of a rheostat 168b. A capacitor 164 blocks the passage of direct current into the windings of generator 162 and serves also to tune the circuit consisting of the generator 162, the transmission line and the transducer to approximately unity power factor. In series with direct-current generator 168 is a choke coil 167 which provides a low-resistance path for flow of direct current and a high-impedance path to minimize flow of alternating current through the windings of generator 168. The uni-directional component of current in the supply lines 37 and 38 (which provides a bias current for the transducer) and the alternating component of current flow by way of lines 37 and 38 through suitable slip rings located at the swivel 3 and thence downwardly through conductors extending through the drill string to energize the transducer for vibration at the resonant frequency of the vibratory column, the length of which is indicated by the dimensional arrow as $\frac{1}{2}\lambda$, representing the wave length at the resonant frequency.

The handling of the drill string and associated operations will, to a substantial degree, be conventional. For example, the cable and its associated pulley system are arranged to support the drill string in tension. There will be provided drill collars (tubular members large in cross-sectional areas) to provide a static load upon the bit 10. The magnitude of the static load upon the bit 10 will, of course, depend upon the weight of the transducer, the weight of the filter, and the weight of the drill collars and any further weight component applied thereto from the drill pipe. In most cases, the desired static load will be provided by the weight of the transducer, the filter, and the necessary number of drill collars. Accordingly, the drill pipe will be maintained in tension.

Torque from the rotary table or driving gears 5 is transmitted through the drill pipe 21, the collars 15, the filter 20, and through the transducer 12 to the bit 10. The invention includes a filter which will transmit both torque and static load and will at the same time provide a low mechanical impedance, as viewed from the upper end of the transducer, at the operating frequency. Structurally, the transducer, the vibrating column, and the filter are strong and capable of withstanding the torque, the static load, and the vibratory movement imparted to the drill 10.

For a frequency of the alternating current of 300 cycles per second, the length of the vibrating column will be approximately 25 feet, corresponding with $\frac{1}{2}\lambda$.

In accordance with the present invention, the vibrating column including the transducer 12 (several modifications of which will be later described) will develop peak forces of large magnitude which result from not only the control of the static load but also from the high power level of excitation of the vibrating column at its resonant frequency. Transducers in accordance with this invention may be operated with an excitation power level in the neighborhood of 200 kilowatts.

At the surface, there is also provided a mud pump 27, driven by motor 27m, which forces drilling fluid or "mud" by way of line 27a downwardly through the drill string, the mud serving the purpose of carrying away chips and fragments and transporting them along the borehole to the surface.

As shown in Figs. 1 and 7, the resonant column extends from drill bit 10 (in the region of the lower dimensional arrow for the length of $\frac{1}{2}\lambda$) upwardly to the first section 20a of the filter in the region marked by the upper dimensional arrow. The vibrating column is shown driven by a preferred type of transducer including magnetostrictive elements 19 and 22, shown in Fig. 2, disposed intermediate the ends of the column.

In Fig. 2, the attachment of the bit 10 to the lower end of the column is accomplished by conventional means, shown as a threaded connection 10a with a short connecting member 11 referred to in the drilling art as a "sub." The sub 11 is threaded at its upper end to the lower end member 12a of the magnetostrictive motor 12. Extending through the motor 12, the sub 11 and the bit 10 is a cylindrical mud passage 13. The upper end member 12b, Fig. 7, of the magnetostrictive motor 12 is rigidly secured as by a sub 14 to the lower end of the first section 20a of the filter as by a tapered threaded connection. The first section 20a of the filter has a weight per unit of length greatly reduced from that of the vibratory column and transducer, preferably not exceeding one quarter the weight per unit length of the transducer. The section 20a of the filter is about half the length of the vibrating column and has a length approximately one quarter the wave length at the resonant frequency of the vibratory column.

Above the first section 20a of the filter as shown in Fig. 8, is a second section 20b of greatly increased weight per unit length. The weight per unit length of section 20b may be the same as that of the transducer and preferably at least about four times that of section 20a. The

section 20b has the same length as section 20a. Above the section 20b of the filter, Figs. 8 and 9, is a third section 20c, which may be of the same construction and characteristics as the section 20a.

The upper end of the third section 20c, Fig. 9, is threadedly connected to the lower end of the drill collar 15 having a large weight per unit length, which may be the same as that of the transducer or of the heavy section 20b of the filter. One or more lengths of drill collar may be included to supply increased static load upon the bit 10 by way of the filter and the transducer, the upper end of the uppermost drill collar being threadedly connected to the lowermost section 21a of the drill pipe by means of coupling member 39. As shown in Fig. 10, a multiplicity of lengths of drill pipe 21a-21w extend upwardly to the point of attachment with the Kelly at the surface. The mud discharge line 72a is shown extending from the blow-out preventer 72.

As indicated by the break between the upper and the lower halves of filter section 20b, Fig. 8, any desired number of filter sections may be utilized. Three sections, as above described, in conjunction with the drill collar 15 have been found adequate for most applications. It also has been found that the heavier sections of the filter may be made from drill collar while the lighter sections may be made from drill pipe, a matter of considerable economy in construction, to obtain the weight ratios per unit length of about 4 to 1. The foregoing ratio may be as low as 2.5 to 1, the higher ratio in general being preferred. Moreover, the first section of the filter above the vibratory column 12 has an impedance less than that of the column and by a factor of at least 2.5. The second section of the filter has a mechanical impedance greater than the first section and by a factor of at least 2.5, and preferably 4. The mechanical impedance as used herein is defined as the product of the mass per unit length multiplied by the velocity of propagation of longitudinal waves. Of course, the filter will include a plurality of sections respectively and alternately different one from the other in the same way as the first and second sections differ.

From the standpoint of transmitting static load and of exerting torque upon the bit 10, the filter 20, and the transducer 12 comprise rigid elements of adequate strength.

The transducer 12, Figs. 2 and 3, between the cylindrical members 19 and 22 has a winding 18 supplied with current from lines 37 and 38, Fig. 1, as described above, by way of conductors 23 and 24 which appear in Figs. 2, 3, and 7. The provisions for the current flow downwardly through the drill string as by way of a suitable transmission line have been omitted in Figs. 8-10 to simplify the small-scale drawings. Drawings made with a larger scale and illustrating a suitable transmission line will be later described.

With the unidirectional and alternating components of current flowing by way of connections 25 and 26 to the winding 18, the magnetostrictive members 19 and 22 lengthen and shorten with change of the magnetic flux through them and thus set the column into vibration. The resonant column itself has a length which, in view of the materials utilized, has its lowest resonant mode of longitudinal vibration at some frequency within the range of frequencies found to be most suitable for the driving of the bit 10 into and out of engagement with the rock; namely, 100 to 1000 cycles per second. Notwithstanding the fact that the upper end of the resonant column $\frac{1}{2}\lambda$ is rigidly connected to the lower end of filter section 20a, the mechanical impedance provided by the filter imposes little restraint against its lengthening and shortening action at the resonant frequency. The transducer 12 as a whole has a high Q, Q being proportional to the amount of energy stored in the vibratory column to the energy lost per cycle. A large part (approaching 60 percent in some cases) of the energy lost per cycle

is expended in driving the bit 10 into the rock or strata 17.

With the bit 10 just out of engagement with the rock or surface or strata 17 and the column excited at approximately its resonant frequency, the bit will be driven with sinusoidal motion with maximum displacement thereof. As the bit 10 engages the strata, the motion of the bit is diminished and so is the Q of the system. But as the Q is reduced by impact with the strata, the force expended in driving the bit rises. By establishing the optimum on-time discussed above, with rotation of the bit 10, and with high power-level excitation of winding 18, high rates of rock penetration are attained.

Attention will now be directed to more detailed features of construction by means of which the transducer may be operated at power levels of an entirely different order of magnitude than heretofore realized. The increased drilling rates described above can be attained only if sufficient power be supplied to the transducer and used by the transducer in reciprocating the bit 10. However, utilization of power in the neighborhood of 100 kilowatts at the bottom of a drill hole 2 or 3 miles deep gives rise to problems not solved in other applications of transducers. The difficulty is increased by reason of the fact that the temperatures at the bottom of the drill hole may be quite high, in the neighborhood of 300° F. The hydraulic pressure of the ever-present liquid is also quite high. Thus, the transducer must be capable of operating at high ambient temperature and under high hydraulic pressure. Its own temperature rise, due to inherent losses, must be maintained below damaging values, and the transducer must be able to withstand abrasion as well as to have a relatively long life while developing high output to drive the bit 10 into and out of engagement with the strata 17.

The preferred transducer of Figs. 2-6 meets all of the foregoing requirements. The magnetostrictive elements 19 and 22 have large cross-sectional areas. They have enclosed between them the energizing winding 18. They are rigid and structurally strong, having, as far as the static load is concerned, a capability of transmitting that load to the bit 10. They are also made up of a plurality of laminations, each electrically insulated from the other except at the ends thereof and together forming low reluctance paths for magnetic flux produced by energization of winding 18. The laminations themselves, made of nickel, though they can be made of nickel-iron alloys or iron-cobalt alloys or other materials, possess magnetostrictive properties and they also possess favorable electrical, thermal, and mechanical properties.

The magnetostrictive transducer of Figs. 2-6 has the capability of withstanding the tensional and compressional stresses due to the lengthening and shortening of the magnetostrictive members 19 and 22, and the torsional forces transmitted through members 19 and 22 from the drill string to the rotating bit 10.

As will be seen from Figs. 2 and 3, the transducer 12 and the vibrating column) has a uniform inside and outside diameter throughout its length. There are no projections. The transducer as a whole presents smooth internal and external surfaces along which the mud flows to and from the strata engaged by the bit.

The preferred modification comprises circular arrays of laminations with each lamination extending generally or approximately in a radial direction. In avoidance of the need to make each lamination wedge-shaped, the laminations may be first assembled together in groups to form rectangular subassemblies. These are then machined to provide sectors. The inner sectors are preferably of the same shape, one of them being identified by the bracket 19a. The outer subassembly is identified by the bracket 22a. The sectors, complementary to each other, respectively form the inner and outer members 19 and 22. The laminations are treated prior to their grouping in the subassemblies to form over their surfaces an electrical insulating coating. The coating should be strong and adherent. Nickel oxide, a suitable coating, will be formed

by holding the laminations, before assembly, at high temperatures, of about 1500° F., for a period of time of about 90 minutes. The laminations themselves are then bonded together into the subassemblies with a strong, rigid bonding agent, so that each subassembly is exceedingly rigid. The subassemblies after machining and finishing are then bonded together to form the solid tubular members 19 and 22. The adhesive or bonding agent may be a high temperature-resistance polyester or epoxy adhesive. At the present time, bonding agents of the nitrile rubber phenolic-type are preferred.

Some precautions are necessary in fabricating each of the sectors 19a and 22a. For example, after they are bonded together in rectangular configuration and as a finishing operation are machined to size, there is a tendency for extended edges of one lamination to contact an adjacent lamination. It has been found that the separation between laminations can be restored by etching each sector, as by a dilute acid followed by thorough washing.

Where nickel oxide is not used as the insulating agent, as for transducers made from the iron-cobalt alloys, it will be preferred to include a thin insulating material between laminations, for example, woven glasses available on the market with a thickness of approximately 1 mil. The bonding agent itself, though of electrical insulating character, cannot always be depended upon to provide the necessary electrical insulation because of its tendency to form a discontinuous film.

By providing relatively thin laminations electrically insulated one from the other, there is minimized the heating of the members 19 and 22 by eddy currents induced by the rapidly changing flux of high density in members 19 and 22.

To produce maximum output for a given input, the cross-sectional areas of the nickel members 19 and 22 are made as large as possible. As the included angle of sectors 19a and 22a is increased, greater eddy currents will be produced. With laminations each having a thickness in the neighborhood of 0.03 inch, an included angle for each of the sectors 19a of about 20 degrees may be used for frequencies up to about 1000 cycles per second. With the sector-type construction shown in Fig. 3, other dimensions of other transducers being the same, more nickel can be used in members 19 and 22, since less bonding material is required. The increase is in the neighborhood of 2.5 percent. The sector type construction also lends itself to the insertion of thin metallic separators where it may be desired to improve the heat flow from members 19 and 22. While the inserts, which may be of copper, have not been found essential, they can be provided and can occupy 2 percent of the volume, leaving a net gain in total volume of nickel over a strictly radial type of transducer later to be described.

In order that winding 18 may be enclosed between members 19 and 22, the laminations of member 19 intermediate their ends are of slightly smaller outside diameter to provide a recessed channel indicated at 19c in Fig. 2. The turns of winding 18 are wound into the channel 19c over a layer of suitable insulating material (not shown) such as fiber-glass cloth impregnated or coated with a silicone rubber compound. The outside of the coil is covered by similar insulating material, also omitted from Figs. 2 and 3 for purposes of clarity.

The outer cylindrical member 22 closely fits over the inner cylindrical member 19. It is important that both cylindrical members 19 and 22 be of somewhat greater length than the winding 18 and shall extend in an axial direction away from the ends thereof for a considerable distance and for a distance adequate to reduce to a negligible value the reluctance between them. Since both members extend a substantial distance beyond each end of winding 18, flux produced by that winding traverses low reluctance paths between members 19 and 22 adjacent the ends of winding 18 and inwardly spaced from their ends. The reluctance is low near the ends of the

winding 18 for two reasons. First, the air gap spacing between members 19 and 22 is of a low order because of the close diametral fit of members 19 and 22 in the regions beyond the respective ends of winding 18. Second, the areas of the closely spaced inner and outer members in the regions of the air gaps are large. Accordingly, closely spaced cylindrical surfaces of members 19 and 22 provide a reluctance so low that nearly all of the magnetic flux produced by winding 18 crosses the air gaps in the regions adjacent the ends of the winding 18.

In accordance with the present invention, the members 19 and 22 are made long enough so that in the regions of their extremities the flux density is of a very low order.

15 The provision of the low reluctance paths adjacent the ends of the winding 18 with resultant low flux densities in the regions adjacent the ends of members 19 and 22, makes possible another feature of the invention. The ends of the laminations of member 19 20 may be intimately joined, as by welding, to laminated or unlaminated ends without production in the resulting solid ends of excessive temperatures by the alternating flux produced by winding 18. By welding the ends of the laminations of members 19 and 22 together and 25 welding both of them as shown at 19d and 19e (and at 19f and 19g) to subs 12a and 12b, there are provided strong joints which also prevent damage to the laminations during the development of drilling forces of great magnitude.

In connection with the welding of the ends of the 30 laminations, it is important that in the end zones the nickel oxide shall be removed. Otherwise the welds will likely be porous and unsatisfactory. The oxide can be removed by sand blasting or chemically as by immersion in electropolishing baths. In making the welds,

35 certain other precautions are also necessary. To prevent the destruction by welding temperatures to the bonding material, which secures together the adjacent laminations, the members 19 and 22 are immersed in a cooling agent such as water to within an inch or so of their ends. The welding is then done without damage to the bonding

40 agent in regions spaced from the welded ends. Preferably no bonding agent is provided in the region to be welded, since the weld itself will provide the necessary mechanical support and the presence of a bonding agent might contaminate the weld. While this region may later be filled with a bonding agent by vacuum impregnation, the bonding agent is not required for mechanical support.

45 Stresses which may arise as the result of welding may be sufficiently relieved without annealing by hammering or peening each layer of deposited weld material. 50 This fact is of importance, since the annealing temperatures which would be required are within the range of those which are likely to damage any selected one of the bonding agents.

The transducer as a whole is preferably provided with 55 casing 28 which may be of metal, such as stainless steel, a layer of insulation being disposed between the ends of the laminations and the casing to provide some resiliency and to act as a buffer to prevent or limit damage to the laminations in case blows are encountered which 60 might dent the outer sheath.

In some cases, it will be desired to provide an inner 65 sheath 29 which may be of an abrasive-resistant resilient material. It may be similar to the external sheath or casing 28 with its resilient layer or it may comprise one of the nitrile rubber phenolic materials.

In the region of the motor or transducer 12 are shown 70 the conductors 23 and 24. The conductor 24, Figs. 2 and 7, is terminated at the upper end of winding 18 and is there connected to it as by a lug 25. The other conductor 23 extends through a slot 22c, Fig. 6, provided in the laminations of a sector 22b of outer cylindrical member 22, to its point of connection at lug 26 to the opposite end of winding 18. As already mentioned, additional lugs may be provided to connect a plurality of coils of the winding 18 in parallel. It is to be under-

stood that the slot 22c and a similar slot for the other conductor 24 will be filled with electrical insulating material during final assembly.

While the members 19 and 22 are lengthened and shortened to actuate the bit 19, it has been found that no special provisions need be made to take care of change in axial length of the coil during operation. Accordingly, after the coil 18 is wound into the recess or slot 19c, it may be rigidly secured by a suitable potting agent. The potting agent may comprise an unsaturated polyester resin containing triallyl cyanurate (American Cyanamid's P. D. L. 7-669). The triallyl cyanurate (TAC), is a high temperature-resistant monomer. Other suitable potting materials include epoxy resins and other resins having 100% solids. Solvent does not escape during curing and they have low shrinkage and are temperature resistant to as high as around 400° F.

The single layer winding 18 is preferred over multiple layers. It permits higher flux densities through larger volumes of magnetostrictive material since it occupies a minimum volume per unit length of transducer. The single layer is also preferred because it is disposed in good heat-conductive relation with both inner core member 19 and outer core member 22. The smooth inner and outer cylindrical surfaces minimize pressure drop as the mud is circulated through and around the transducer, and there is avoided any change in cross-sectional area which, if present, would couple the longitudinal vibration of the transducer to the drilling fluid or mud and produce damping of the transducer.

With the construction of the transducer as above outlined, and with power supplied to the winding 18 of a magnitude around 100 kilowatts or more, the members 19 and 22 will have produced through them flux densities which change rapidly from values approaching saturation to values near zero. With such a high power density, rates of heating losses which could be tolerated in smaller units would produce damaging temperature rises in the large unit. However, transducers in accordance with the present invention have their temperature rises limited not only by the provision of good heat paths but also by the absence of heat-transfer barriers. For example, the winding 18 through dividing the transducer 26 does not form a barrier against transfer of heat. Heat flows toward the flow channel 13 from member 19 and it flows outwardly from member 22. In previous designs, the temperature rise has imposed a power limitation below the maximum at which magnetostrictive materials could be effectively used. However, in accordance with the present invention, the power delivered to the winding 18 produces flux densities which approach the maximum which will give rise to an increasing magnetostrictive action. Thus, the magnetostrictive transducer can be operated, as regards its electromechanical power-converting action, near the theoretical maximum. For example, a transducer a half wave length long for a preferred frequency range of from 300 to 400 cycles can be operated at a power level as high as 200 kilowatts.

Multiple-motor transducers

Transducers embodying the present invention may be connected in tandem or cascade. For example, in Fig. 12, there are shown two transducers 58 and 59 each one-half wave length long and rigidly connected together by a coupling 60. By exciting the two transducers 180° out of phase, the assembly vibrates at the resonant frequency with maximum displacement of the bit 10.

If the connecting member 60 of Fig. 12 were a drill collar, one-half a wave length long, the two transducers 58 and 59 would then be excited in phase and the one and one-half wave length vibratory assembly would produce maximum displacement at the bit 10.

Modified transducer construction

As mentioned above, transducers of other types may be utilized in conjunction with many features of the

present invention and magnetostrictive transducers may be made in different ways. When tapered nickel strip of suitable width becomes commercially available, the transducer of Fig. 13 may on a cost basis be competitive with the preferred construction of Figs. 2-7. In Fig. 13, the mud passage 13 is open and unobstructed. In contrast with the sector construction, the laminations 19a are of like shape, each extending radially of the transducer. The winding 18 is wound into a recess as explained above. The return path for the flux is provided by the outer laminations 22d, each of which is tapered and radially disposed. Between the outer casing 28 and the circular array of laminations is a layer 28a of the potting compound, which acts as a cushion minimizing damage to the transducer during drilling and during handling. Connections are made to winding 18 in manner similar to that described for the modification of Figs. 2-7. A slot is provided in the inner member 19 to receive the conductors 23 and 24. In the regions where the ends of winding 18 are connected to the conductors, the recess is enlarged to form pockets within which connecting lugs may nest. The lug 23c, which appears in Fig. 13, is attached to conductor 23 and to one end of the winding 18 by any suitable means, preferably as by hard soldering. The conductor arrangement of Fig. 13 may of course be used in the modification of Figs. 2-7 and is preferred in that the winding 18 and conductors 23 and 24 are then assembled together on member 19, which is an advantage from the assembly standpoint, and is somewhat helpful in other respects in that the conductor-receiving slots are provided in the member 19 of the greater radial dimension.

Further advantages of transducers of the type already described will be apparent with reference to the modification of Fig. 14. The inner casing or liner 29 and the laminations 19a of member 19 are of the same type as in Fig. 13. The laminations of the outer member 80 are formed of good transformer steel having higher permeability and higher maximum working flux density than the magnetostrictive material. One such transformer steel is that sold under the trade name "Trancor XXX." Member 80 provides a return path for the flux and is itself surrounded by a motor casing 81 of considerable thickness. The member 80 and the casing 81 preferably made of steel provide greater mechanical protection against damage. Inasmuch as the magnetostrictive member 19 is the active part and the outer member 80 serves only as a return path for the flux and is not lengthened or shortened by change of flux therein it will be understood that the "subs" or connecting members are welded only to the ends of the member 19. There is retained in the transducer of Fig. 14 the feature of low reluctance for the return path of the flux in that beyond both ends of the slot which receives the winding 18 the inner member 19 is in close proximity with the outer member 80. With the close spacing and the large area the reluctance is made low. In Fig. 14 the slot receiving the winding 18 is preferably provided in the outer member 80. Thus, the only reciprocating part is the member 19, the ends of which are attached only to the bit and to the filter.

While a transducer of the type shown in Figs. 15 and 16 has operated satisfactorily, it lacks the central unobstructed mud passage, and the return path for the flux does not surround the coil windings. The mud passage, Fig. 15, comprises the two flow channels 13a and 13b each of which is preferably lined with an abrasive-resisting coating such as one of the synthetic rubbers. The lining 81 resiliently separates the motor from the outer motor case 82. The magnetic structure including the winding is of the "double-D" configuration. One D-shaped leg comprises the laminated core 83a about which are the turns of the conductor forming one coil 18a of the winding. An end of that coil is connected to one supply line 24 by the lug 25a. The other D-shaped

leg comprises core 83b having a coil 18b one end of which is connected to supply line 23 by lug 26.

As shown in Fig. 17 (at reduced scale) the cores 83a and 83b are formed by slotted laminations which beyond the respective ends of the central slot or opening 84 are relatively long. Thus the flux paths between legs or cores 83a and 83b as shown by the broken lines 85 and 86 are spaced inwardly from the ends of the motor 12. As earlier explained, by providing low reluctance paths adjacent the ends of legs or cores 83a and 83b the flux between them does not with any substantial strength traverse the outermost ends of the laminations. Hence they may be solidly welded together as indicated at 87 and 88 without production of eddy-current heating of consequential degree. In Fig. 17, the threaded end members (such as 12a and 12b of Figs. 2 and 7) have been omitted.

Since the contraction and expansion of the nickel laminations due to their magnetostrictive properties is a function of flux density, the coils 18a and 18b are preferably wound series-aiding, that is to say, so that they produce in the core as a whole, magnetic flux of the same instantaneous polarity. In the diagrammatic sketch of Fig. 16, the arrows drawn on certain turns of coils 18a and 18b show the direction of current flow for one-half cycle of current. Thus the flux as shown by the arrows in Figs. 16 and 17 is in the same or aiding direction in the laminated core 83. The manner in which the ends of coils 18a and 18b may join with supply lines 23 and 24 is schematically suggested in Fig. 16. Details will be later described.

Many further variations in motor construction may be made. For example, in Fig. 18, in a rather heavy motor case 90 is a driving member 91 formed of nickel laminations which, at the respective ends, is welded to sub. Member 91 is magnetically coupled to member 92 by low reluctance flux paths provided in manner already described (Fig. 14). The laminations of member 92 may be of transformer steel (as "Trancor XXX") about which may be wound the winding 18. The unit as a whole is enclosed within an abrasive-resistant rubber sheath 94. In the design of Fig. 18, the laminations are assembled in small groups of rectangular shape. Machining or grinding may be used to achieve a close fit with the cylindrical housing or case 90. While a gain in the quantity of active material would be achieved with a correspondingly higher cost of construction, the stepped arrangement of Fig. 18 may be preferred. A compromise design may be used, as by construction any "double D" design with each lamination rectangular but each one different in width from the other, thus reducing the size of the triangular-shaped spaces of Fig. 18.

Another form of "double D" transducer is shown in Fig. 19. It is quite similar to the design of Figs. 15-17 but illustrates the fact that the edges of the laminations forming cores 95 and 96 may face the mud passages. In Fig. 19, the laminations of the respective legs 95 and 96 of the "double D" are of uniform width except at their extremities.

In the modification of Fig. 20, the cores 97 and 98 of a "double D" configuration together with coils 18a and 18b are circular in cross section and of smaller diameter than the motor case or housing 99. Thus an annular mud duct 100 is provided between the housing 99 and the motor proper. While the housing may be rubber lined, only the motor element is shown encased by a protective sheath 112.

Modifications more complicated to construct while within the scope of the present invention are not preferred because of fabrication and assembly costs. For example, in Fig. 21, four cores 101, 102, 103, and 104 with housing 105 have coils 106-109 respectively wound about them. A mud passage 110 of rectangular shape (in cross section) extends diametrically across the housing 105, a

metallic liner 111 being shown, though one of abrasion-resistant, flexible, resilient material may be used. The coils 106-109, connected to supply lines 23a-23b and 24a and 24b are wound and energized to meet the requirements set forth in connection with Fig. 16, namely, so that all coils are magnetically in aiding relation for production of maximum flux densities in the cores 101-104.

In the several forms of transducers which have been described, at least one member is always made of laminations of magnetostrictive material while the laminations of the other member forming a return flux path are made either of magnetostrictive material or of one magnetic material. Because of the limitations upon the space available for the transducer in a bore hole, where the return path for the flux is made of transformer steel or the like, the area of that member may be made less than that of the magnetostrictive material because of the high permeability at high flux density of the transformer steel. Accordingly, the cross-sectional area of the members 19 and 22, Figs. 2 and 3, or members 19 and 80, Fig. 14, may be and are related inversely as their maximum working flux densities. The latter phrase means to the magnetostrictive materials there will be applied a maximum magnetomotive force of a magnitude to produce a certain maximum working flux density therein. The maximum working flux density of the return path will be selected to lie in the region of the knee of the magnetization curve for the material used where it is a silicon transformer steel such as that sold under the trade name of 30 "Trancor XXX."

Further transducer theory

Recalling the fact that the lengthening and shortening of the magnetostrictive element arises due to the change in density of the flux, it may be concluded that such an element will move between extreme limits each time the alternating exciting current changes from maximum to minimum. If the core flux is attributable only to the presence of alternating current in an exciting winding, such changes occur twice per cycle of alternating current and the frequency of vibration will be twice that of the alternating current. Operations of the foregoing character are portrayed in Fig. 22 where the alternating current is represented by the sine wave 151. The amplitude of movement of the core is shown by the sine wave 152 which has a frequency twice that of graph 151.

The foregoing operation changes if unidirectional magnetic flux be maintained in the magnetostrictive element as by inclusion of a permanent magnet in the core structure or by including the direct current component of field excitation described in connection with Fig. 1. Fig. 23 illustrates by graph 153 a frequency of movement corresponding with alternating current excitation represented by graph 151. Thus, as the alternating current rises in a direction aiding the unidirectional flux, it rises to a maximum and returns to its original, or average, value shown by broken line 154 when the flux, due to the exciting current, is again zero. As the current reverses and the magnetomotive force reduces the flux in the magnetostrictive element, the flux is reduced to a minimum value, returning to its initial value as the negative half-cycle ends.

Though the transducers may be operated without unidirectional bias, there are advantages in favor of a biased operation, the principal one being a greater efficiency, i. e., a greater conversion of electrical energy to the desired mechanical energy. As shown in Fig. 25, the bias current will be selected for development of the maximum force by the transducer.

For a given length of magnetostrictive motor assembly under given conditions of operation, there will be an inherent resonant frequency. The advantages of operating at the resonant frequency are graphically shown by the graph 155 of Fig. 24, plotted with dynamic strain as ordinates and frequency as abscissae. At the resonant frequency f_r , the maximum dynamic strain is developed and

its magnitude decreases quite rapidly as the operating frequency rises or falls below resonance.

In Fig. 26, the winding 18 is shown connected to conductors 23 and 24. The apparatus to the left of the broken line 161 is located outside the borehole and comprises an alternating current source 162 supplying the primary winding of a transformer 163. The secondary winding supplies through a line capacitor 164 alternating current to winding 18. Direct current is also supplied winding 18 by any suitable source 168, such as a direct current generator, the direct or unidirectional current flowing through a conductive circuit including an inductance or choke coil 167. The impedance of the coil 167 must be several times greater than the impedance of the winding 18 in the frequency range over which the alternating current generator is operated. Thus, little alternating current flows through the branch including coil 167 and direct current source 168. The capacitor 164 represents a practically infinite impedance to the direct current and eliminates its flow in the transformer circuit. Thus the direct and alternating current circuits are effectively independent of each other and yet both do supply the needed power to winding 18 by way of the single pair of line conductors 23 and 24. Alternatively, transformer 163 may be eliminated by proper selection of the operating characteristics of alternating current source 162, as shown in Fig. 27.

Where two transducers are directly connected together, it will be remembered from Fig. 12 that there is a phase shift of 180 degrees in strain between the adjacent one-half wave-length sections. Tandem connected transducers each a half wave length long are shown in Fig. 28 with conductors 23 and 24 extending upwardly therefrom. In Fig. 29 there is shown a system of operating the transducers, only two conductors 23 and 24 being required. These supply conductors are connected to a supply system of the type already described and as shown in Fig. 26. The alternating current generator 162 is shown in Fig. 29 as being driven by a prime mover 175 and the direct current generator 168 driven by prime mover 175a.

In the region of the transducers 58 and 59 and occupying a minimum of space within the transducer housings is a system which provides for flow of direct current in one direction through winding 18a of transducer 58 and in the opposite direction through winding 18b of transducer 59. Assuming conductor 24 to be of positive polarity, direct current will flow from direct current generator 168 by way of the inductance or choke coil 167 to the conductor 24 extending downwardly through the drill string. In the vicinity of the transducers a branch circuit including an inductance 176 takes the current to the junction 177 between windings 18a and 18b. The direct current then divides, flowing in one direction through winding 18a as indicated by arrows 178 and in the opposite direction through winding 18b as indicated by arrow 179. The return path from winding 18a is by way of a resistor 180 connected to conductor 23 and from winding 18b is by way of conductor 24a and inductance 181. Blocking capacitors 182 and 183 provide low impedance paths for the alternating current and the inductances 176 and 181 high impedance paths for that current.

By designing the circuit components to take up a minimum of space, as by semijannular plates of the needed capacitors and similarly constructed chokes and resistors, location of components in the vicinity of the transducers does not present a major obstacle.

Since the direct current flow through windings 18a and 18b is in opposite directions, the respective transducers are oppositely biased. Thus, in Fig. 30 the direction of the bias current for winding 18a may be in the direction and of the magnitude indicated by the arrow 186 while the arrow 187 extending in the opposite direction from zero line 188 represents the bias current for winding 18b.

Since the alternating current flows through the wind-

ings 18a and 18b in the same direction as by way of conductor 24, capacitor 182, conductor 24a, windings 18b and 18a and by way of capacitor 183 to conductor 23, it will produce magnetic flux in one winding in the same direction as the bias current and in the opposite direction in the other winding at the same time. Thus, in Fig. 30 there is shown by graph 190 one cycle of alternating current which during the first half cycle increases the flux to a maximum 190a and then reduces it to a minimum 190b. At the same instantaneous times, the alternating current as shown by graph 191 below the zero line, produces a flux opposing that developed by the bias current 187. Thus as the flux is maximum at 190a, it is minimum at 191a and as it is at a minimum at 190b it is at a maximum at 191b.

In terms of strain developed by the transducers 58 and 59, the situation is represented by graph 190 and by graph 192, shown in broken line, and displaced in phase one hundred and eighty degrees from graph 190. The described result meets the requirements of transducer operation with a phase displacement of one hundred and eighty degrees. Thus the forces developed by transducers 58 and 59 are in the correct phase to enhance the action each of the other and to result in a higher force for reciprocation of the bit 10, than would be developed by either transducer acting separately and higher than the sum of the forces produced by each transducer acting separately. Use of the two transducers 58 and 59 in tandem results in an increased strain level in the vibrating column, as implied above. Each transducer operates in an improved manner because of the increased strain level (which develops inverse magnetostrictive effects to a greater extent) and each transducer is capable of greater power output and more efficient operation than would be possible with either transducer operating alone in the same resonant column.

In some applications of the invention, a three-wire system may be provided in the drill string. For such an application, the arrangement of Fig. 31 may be employed. The windings 18a and 18b are by conductors 23 and 24 connected in a series circuit including the secondary winding of transformer 163. That winding is center-tapped and includes the direct-current source 162 in the circuit extending from the center tap by way of conductor 24b to the junction between windings 18a and 18b. Thus, the alternating current flows, during a given half-cycle, in the same direction through windings 18a and 18b, while the biasing current flows in one direction in the winding 18a and in the opposite direction in the winding 18b. Arrows 184, for a given half cycle, show the flow of the alternating current while arrows 178 and 179 again show the direction of flow of the direct current. Accordingly, the graphs and explanation of Fig. 30 apply to Fig. 31.

The advantage of the system of Fig. 31 is the avoidance of additional circuit components located within the borehole.

In the system of Fig. 32, the alternating current from transformer 163 flows in series by way of conductors 23 and 24 through transducer windings 18a and 18b. Bias current is provided by a rectifier 194 connected by resistor 195 and conductor 198 in shunt with winding 18a. A rectifier 196 in a similar circuit but oppositely poled supplies bias current through resistor 197 by way of conductor 198 for flow through winding 18b in the opposite direction from the bias current in winding 18a. Thus, the proper phase relationship between the flux in the transducer windings is provided. In Fig. 30, the foregoing is illustrated in terms of the fundamental component of the alternating flux.

If the bias current flows through both of windings 18a and 18b in the same direction, then the alternating current, for the one-hundred-and-eighty degree phase shift, must flow through them in opposite directions. This condition of operation can be provided by reversing the connections to one, but not both, of the windings 18a, 18b.

For example, the upper end of the winding 18b can be disconnected from the common conductor 24b, as shown in Fig. 31, and connected instead to the conductor 24, and the lower end of the same winding can be disconnected from the conductor 24, as shown, and connected instead to the common conductor 24b. The graphs 205 and 206 of Figs. 33 and 34 respectively show the change in flux in transducer elements for corresponding half cycles of alternating current. Since the direct current is in the same direction in both the windings 18a and 18b, the lines 207 are drawn on the same side of the zero axis. However, when a half cycle of alternating current is in the same direction as the bias current in one transducer, Fig. 33, it is in the opposite direction in the other transducer 59, Fig. 34. Thus, there is a phase displacement of one hundred and eighty degrees as between the two.

In the several power-supply systems, the circuit components in series with the sources of unidirectional current are selected for the desired values of bias current. The optimum value can be determined as already explained in connection with Fig. 25, or that value can be ascertained by direct measurement of the strain developed in the transducer. With the alternating current component held constant, and the bias current varied, a strain gauge 32, Fig. 36, will produce an output as shown in Fig. 35 by the graph 210. The optimum value I_1 for the bias current clearly appears as in the region of the knee of the graph. If the alternating current be doubled in value, then the optimum bias current will have a somewhat higher value shown in the region of the knee of graph 211, as at I_2 .

Further transducer theories

It will be remembered that as the bit 10 attached to the vibratory column engages the strata 17, the extent of movement of the bit is greatly decreased for a portion of the cycle of vibration. For that reason, and for other reasons, the resonant frequency of the vibratory column increases as the static load increases by an amount which depends also on the characteristics of the strata engaged by the bit. In operation, it is necessary to increase the frequency of the alternating current to maintain excitation of the column at or very near (approximating) its resonant frequency. Accordingly, frequency-control is provided which in its simplest form, Fig. 1, may consist of conventional means of changing the speed of the prime mover 175, driving an alternator, i. e., an alternating-current generator 162, which, in turn, supplies the alternating current to the winding 18 of transducer 12. The speed of the prime mover 175 will be adjusted to maintain the development by the transducer 12 of maximum strain in the bit 10, by maintaining the vibrating column substantially in resonance.

In accordance with the disclosure of the copending application for U. S. Letters Patent of George McPherson, Jr., Serial No. 350,732, now U. S. Patent 2,745,998, the difference in phase between the force at the bit 10 or the strain at the center of the transducer 12 and the alternating current supplied to the transducer is used to provide the desired adjustment. The percent of on-time of the bit in engagement with strata 17 may be controlled by adjusting either the power input to the transducer or the static load. The strain gauge 32 may also be attached to the vibrating column near the bit so that the variation of the vibratory force exerted by the bit 10 on the strata 17 with respect to time is measured. On-time and off-time may be obtained from this measurement, the off-time being the portion of the cycle when the force is zero and the on-time being the portion of the cycle when a force is present. Thus the strain gauge 32 can be attached to the bit in the region adjacent the strata 17, to indicate maximum output at resonance or the strain gauge may also be located at the midpoint of the vibrating column where the partial node of vibration and antinode of stress is located. At mechanical resonance, there exists a

ninety-degree difference in phase between the driving alternating current and the stress at the midpoint of the column. This phase difference departs rapidly from ninety degrees and in opposite directions (toward zero degrees or toward one hundred and eighty degrees) as the frequency is changed to either side of the resonant frequency. This type of variation is very well suited for use in automatic control circuitry.

In the present description and in the claims, the terms "node" and "partial node," which are used interchangeably herein, are defined as meaning the region in which the amplitude of the displacement is a minimum, and an "antinode" is defined as the region in which the displacement amplitude is maximum. Graphically, Fig. 36, with the motor 12 and its associated resonant assembly one-half a wave length long ($\frac{1}{2}\lambda$), the graph 30 illustrates the extent of displacement. At the respective ends of the vibrating assembly, the displacement is maximum when the bit end is not loaded by engagement with strata. 10 Midway of that assembly, the displacement is minimum. On the other hand, the greatest force is developed midway of the assembly where the displacement is least. The broken line graph 31 illustrates magnitudes of force over a full wave length. A strain gauge 32 may be located at a 15 node, midway of the assembly, or near the bit end of the resonant column when loaded by engagement with strata for purposes of control of frequency of the power supply to maintain it at the resonant frequency of the power assembly during drilling. More detailed descriptions of 20 control systems will later be presented.

The action of the transducer assembly may be graphically presented in other ways. For example, in Fig. 37, with a static load on the bit 10 exceeding the peak value of the force developed by the bit on the rock, it will be 25 seen that the graph 34 plotted with force as ordinates and time as abscissae represents the variation in the total force applied by the bit 10 on the rock. With the motor 12 developing a force in the same direction as the static force, the total force on the bit will rise to a maximum 30 34a and then will decrease to a minimum value, as indicated at 34b, above zero force, as indicated by "zero" line 35. However, the force on the bit changes from a lower limit 34b to an upper limit 34a. This mode of 35 operation is referred to as "over 100% on-time." The variation between the two limits is referred to as the peak-to-peak dynamic force. As the vibration level is increased in magnitude as by increasing the driving current in the motor 12, the value of the peak-to-peak dynamic force is increased. When the lower limits of the 40 peak-to-peak force just touch the zero line 35, there will be what is termed 100% on-time of the bit with respect to strata. With further increase in the dynamic force, 45 however, the shape of graph 34 drastically changes.

For comparative purposes, the graph 36 of Fig. 38 50 illustrates conditions where the same static force is applied as for Fig. 37 but with a materially increased dynamic force developed by motor 12, and sufficiently increased so that the on-time is less than 100% and with an appreciable off-time. In such case, it will be seen 55 how the peak-to-peak dynamic force has been greatly extended as from the minimum shown at 36a to a maximum shown at 36b.

The rate of drilling depends primarily on the peak 60 value of the total force exerted by the bit on the rock for on-times ranging from approximately 100% to less than 100%. As long as the dynamic force is maintained at a certain peak value, the rate of drilling is 65 practically independent of on-time for on-times of 100% and under and for sufficiently high rates of rotation of the bit. (For low rates of rotation minor improvement is obtained by operating at the lower on-times.) This 70 signifies that as long as the peak dynamic force is equal to or greater than the applied static load (which is the same as saying that the peak-to-peak dynamic force is at least about double the value of the static load) the

rate of penetration is practically independent of the value of the static load. On the other hand, if the peak dynamic force is appreciably less than the static load, the rate of penetration depends only upon the applied static load and is practically independent of the value of the dynamic force. As mentioned previously, for on-times of well over 100%, the rate of penetration is even somewhat less than if the dynamic force were not applied. The mode of operation illustrated in Fig. 38 is thus to be greatly preferred over that shown in Fig. 37. Many of the benefits of vibration drilling are not realized if the mode of operation is like that shown in Fig. 37.

The rate of rotation of the bit has to be adequate in order to achieve the high drilling rates obtainable with vibration drilling. As the rate of rotation is increased, the indexing distance, or spacing between blows at the periphery of the bit, is increased. This results in an improved cutting action per blow since a substantial portion of the intervening material between successive positions of blows is sheared off, provided that the force per blow is high enough. However, when the indexing angle becomes a substantial portion of the angle between successive wings of the bit, no further benefit is accrued by increasing the rate of rotation still further. It has been found theoretically and verified experimentally that the rate of penetration increases in approximately linear fashion with the rate of rotation and then has a tendency to level off at some high rate of rotation. The optimum rate of rotation depends upon the size and type of bit, the peak force, the vibration frequency, and the type of rock. In very general terms, rates of rotation of roughly 100 R. P. M. are required for optimum results with roller bits or star-drill type of drag bits.

Many of the conventional types of rock bits, either of the drag or roller variety, may be employed with advantage in vibratory drilling as embodied in the present invention. Operation at the lower force levels occasioned by vibrating at high frequencies permits the use of inherently faster drilling, but structurally weaker, bits than can be employed with mechanically actuated drilling apparatus vibrating at low frequencies. In general, bits with which higher penetration rates are obtained with conventional rotary drilling will give more than correspondingly higher rates when used with vibratory drilling. Bits employing a smaller number of cutting blades of reduced widths and with smaller included angles at the cutting edges drill faster but are also more subject to damage and to higher rates of wear. However, the rates of wear increase less rapidly for such bits when used with vibratory drilling in the preferred frequency range than with conventional rotary drilling.

The proper bit to choose for vibratory drilling, from among the bits available commercially for conventional drilling, is of necessity a compromise between the desired high rate of penetration and ability to withstand the possible damage due to the forces employed. Conventional roller bits have been found satisfactory for use at lower force levels of vibration drilling; but at the higher force levels suitable bearing surfaces, such as pre-loaded ball or roller bearings, are required.

A typical bit capable of providing high penetration rates in vibratory drilling according to the present invention is illustrated in Figs. 39 and 40. The bit 10' is provided with thin cutting blades 10b-10b having small angles at the cutting edges. A cylindrical opening 13a through the center of the bit 10' provides a continuation of the mud passage through the drill string and includes outlet nozzles 13b-13b, one near each blade, through which the mud flows at high velocity to carry the drilling chips away from the vicinity of the blades 10b-10b. One of the nozzles 13b-13b is visible in the drawing, and the other is similarly located with respect to the other blade. The bit 10' may be secured to the lower end of the vibratory column 12 by means of a threaded connection 10c.

In accordance with the present invention, drilling rates of two hundred feet per hour are attainable with bits having a diameter of $3\frac{3}{4}$ inches, the transducer having a diameter of about 8 inches, energized at 300 cycles per second with power input thereto of about 200 kilowatts.

Frequency control

In order that operation at substantially the optimum or resonant frequency may be maintained, despite the fact that the resonant frequency changes during drilling, a frequency control system is provided to respond to the output of the transducer 12 in such way as to regulate the frequency of the alternating current power in accordance with the changing resonant frequency of the transducer. There may be selected any one of several variables whose magnitudes change with departure of transducer operation from its resonant frequency, such as strain-gauge output. One frequency control system of the McPherson application mentioned above comprises regulating the frequency of the alternating current power supply either manually or automatically in response to phase change as between the alternating current supplied to the transducer and transducer strain in the vicinity of the bit or preferably in the region of the partial node where the wave form of the strain signal is more nearly sinusoidal. In accordance with the McPherson disclosure, it has been found that at resonance a phase difference of approximately ninety degrees exists between the alternating current and the transducer strain. Thus, as this phase angle changes from ninety degrees, the frequency of the alternating current generator or alternator should be changed in the direction to restore the ninety-degree relationship.

Fig. 41 schematically illustrates a system for providing such control, as set forth in the copending McPherson application. The strain-gauge 32 may be either at the bit 10 or at the partial node, as illustrated. The output from the strain gauge 32 is applied to an amplifier 250 whose output is fed to the input terminals of one input section of a phase-sensitive detector 251. A current signal derived from a low resistance 252 inserted in the supply line 24 is applied, preferably through a high-capacitance blocking condenser 253, to the input terminals of the other input section of the phase-sensitive detector 251. The blocking condenser 253 is needed where, as in the circuit of Fig. 41 a direct-current component of power is supplied to the transducer as by the direct-current generator 168 driven by the prime mover 175a and connected through the inductance 167 to the transmission lines 23, 24, in addition to the alternating-current component of power supplied by the alternating-current generator 162 driven by the prime mover 175 and connected through the capacitor 164 to the transmission lines 23, 24.

The phase-sensitive detector 251, preferably of the electronic type known in the art, provides at its output circuit 259 a direct-current potential approximately proportional to any variation from a ninety-degree phase relationship between the strain signal received from the strain gauge 32 and the current signal received from the low resistance 252 (which is unchanged in phase by the capacitor 253). This output potential has one polarity when the phase relationship is greater than ninety degrees and has the opposite polarity when the phase relationship is less than ninety degrees. This output potential is applied to the input terminals of a motor control amplifier 254 which provides an output of sufficient amplitude to operate a motor 255. The direction in which the motor 255 rotates is dependent upon the polarity of the voltage applied to it from the output of the motor-control amplifier 254. It will be positive or negative in accordance with the polarity of the output of the phase-sensitive detector 251.

When the phase relationship between the strain signal

from the strain gauge 32 and the current signal from the low resistance 252 is ninety degrees, the output of the phase-sensitive detector 251 is zero, so the motor 255 receives zero voltage from the motor-control amplifier 254 and remains at a standstill. As the phase angle decreases, however, as by change in the phase of the strain or output of strain gauge 32, the phase-sensitive detector 251 provides an output voltage of one polarity, which, as amplified by the motor-control amplifier 254 and applied to the motor 255, causes the motor to rotate in one direction, a direction which through suitable gearing, as indicated by broken line 257 adjusts a governor 258 to change the speed of the prime mover 175 in the direction, and by an amount, which restores the ninety-degree relationship. A change in the phase of the strain in the opposite direction reverses the polarity of the output of the phase-sensitive detector 251, thereby reversing the direction of rotation of the motor 255, again to restore the ninety-degree relationship.

Considerable attenuation and phase shift may be present in transmitting the strain signal from the transducer to the top of a long drill string because of the characteristics of the line used to transmit this signal. The power transmission line may not be used for transmitting the unmodified strain signal since the strain signal is of the same frequency as that of the very much greater power supply voltage.

To avoid this deterioration in the strain signal, and to avoid the effect of phase shift in the transmission line which may occur between the low resistance 252 and the transducer 12, a sub-assembly including the resistor 252, the strain signal amplifier 250, the phase-sensitive detector 251 and a high frequency carrier-current transmitter (not shown) may be located in a container inserted in the drill string just above the mechanical filter. The output signal from the phase-sensitive detector is then used to modulate the carrier current produced by its transmitter. The modulated carrier signal, derived from the carrier-current transmitter, is transmitted upward along the power transmission line and after passage through a filter in the line is demodulated for development of a direct-current potential proportional to the output of the phase-sensitive detector 251, and whose polarity changes in the same manner as that of the output of said detector. This potential, applied to the input of the motor-control amplifier 254, controls the speed and direction of the motor 255, which in turn controls the speed of the alternator, and thus the frequency, to maintain the ninety-degree phase relationship between the current and the strain signal.

Of course, the governor 258 may be manually adjusted as by a wheel 259 in accordance with deflection from ninety degrees of the phase-angle meter 260. In general, the meter 260 and provisions for manual control are provided even with a fully automatic system.

The soundness of the basis for the control system thus far described has been experimentally verified. In Fig. 42 the graph 261 illustrates the change in phase angle between the strain at the bit 10 and the alternating current supplied to the transducer winding 18. The graph 262 represents the strain at the bit. As the frequency increases, it will be seen that the phase angle decreases from about one hundred and forty degrees, passing through ninety degrees as the strain at the node approaches maximum. The phase angle from about one hundred degrees to about forty degrees rapidly decreases and then more slowly decreases. The maximum strain occurs at a phase angle of ninety degrees within the limits of accuracy of the measurements.

The graphs 263 and 264 of Fig. 43 respectively correspond to those of Fig. 42 but the graph 263 represents phase angle between the alternating current supplied to winding 18 and the output of strain gauge 32 located at the nodal point or partial velocity node, as in Fig. 41. The angles have a minus sign since the strain at the par-

tial velocity node is one hundred and eighty degrees out of phase with the strain at the bit 10. The region of maximum strain occurs, graph 264, in the region of ninety degrees.

The steepness of the change of phase angle of both Figs. 42 and 43 is a function of the Q of the transducer. It can be shown that Q equals the product of one-half the resonant frequency times the rate of change of phase with respect to the frequency at resonance. The higher the Q the steeper will be the slope of graphs 261 and 263 in the region of ninety degrees. Thus, while band width at the resonant frequency is decreased corresponding to an increase in Q, the sensitivity of control is increased and the control system of Fig. 41 will function to maintain the transducer operating at its resonant frequency. For a decreased Q, the sensitivity of control is decreased but, for this case, the frequency of operation need not be controlled to within as close limits as for higher Q operation because of the increased band width. Thus, this automatic control system will function satisfactorily over a wide range of Q values.

Further, in accordance with the McPherson application, advantage has been taken of the fact that the resistive component of the transducer impedance has been found to be a maximum at a frequency not far removed from the resonant frequency of the vibratory column. By reason of that fact and of a known relationship in electrical theory, a control system of a different type may be utilized, such as shown in Fig. 44. This second form of control system obviates the necessity of obtaining any signals from down-hole sensing elements. The system functions in a manner to produce maximum power input to the transducer when a substantially constant current is supplied thereto. With power output determined by the product of the circuit resistance and the square of the current, high transducer output will be maintained by adjusting the frequency in response to change in the resistive component of the transducer impedance. The control action is in a direction to raise or lower the frequency as needed to maintain the resistive component of the transducer impedance at a value approaching its maximum.

In its simplest form, and with the current held constant by any suitable means as by manual adjustment of generator excitation or by any well-known automatic constant current-control circuit, as one operating on the exciter system, the alternator frequency is varied by changing the governor setting as by the adjusting wheel 259, shown in Fig. 41, to maintain a maximum reading of a watt meter 500 responsive to the power transmitted to the transducer through conductors 23 and 24. Attached to the shaft of the watt meter 500 is a contact arm 501 movable between a mechanical bumper 502 and an electrical contact 503. The bumper and electrical contact 503 are mounted on a light-weight vane 504 which is pivoted on, and rotatable relative to, the meter shaft which carries the pointer and the contact element 501. Accordingly, when contact arm 501 is rotated in a clockwise direction during periods of increasing power, the contact 501a is moved against the contact 503. Arm 501 then moves vane 504 in a clockwise direction maintaining closed a circuit through contacts 501a and 503. During periods when the power output of alternator 162 is decreasing the contact arm 501 first opens said circuit and then engages the bumper 502 to move the vane 504 in a counterclockwise direction. The contact arm 501 may, if desired, serve also as the indicating needle of the watt meter 500.

The manner in which the relative movement between the contact arm 501 and the contact-carrying vane 504 automatically adjusts the governor 258 to maintain maximum power flow in lines 23 and 24 will now be explained. The armature of motor 255 which adjusts the setting of the governor 258 is energized from any suitable source of direct voltage 508 by way of slip

rings 509 and 510 and direction-controlling commutator contact segments 511 and 512. As shown, the motor 255 with its field winding 255a, energized from a suitable voltage source, will rotate at low speed in one direction. It is rotated at low speed by reason of the inclusion in the motor circuit of a speed-reducing resistor 513. When the positions of contacts 511 and 512 are reversed, the direction of rotation of motor 255 is, of course, reversed.

By driving the segments 511 and 512 at relatively low speed as by a motor 514 of the type having a geared-down output shaft, the motor 255 adjusts the governor 258 first in a direction to increase the speed of the prime mover 175 and then in a direction to decrease its speed. The extent of the adjustment is small and is insufficient to make more than a slight change in frequency of the alternator 162. Sufficient change, however, is made in the frequency for the response of the wattmeter 500 to indicate whether or not increased power results from an increase in frequency or whether decreased power results therefrom.

It will now be assumed that the motor 255 is rotating in a direction to increase the frequency of alternator 162 and that the power through lines 23 and 24 to the transducer is increasing. Accordingly, a circuit will be completed from one side of a voltage source 515 through an operating coil 516 for a relay contact 517 and through the contacts 501a and 503 to the other side of the voltage source 515. The relay contact 517 closes to remove the resistor 513 from the motor control circuit as by placing a short circuit around it. The effect of short-circuiting the resistor 513 is to increase the speed of the motor 255. Thus, when increasing frequency results in an increase in power, the motor 255 runs faster in the direction to increase the frequency of the alternator 162. As soon as the positions of the commutator contact segments 511 and 512 are interchanged from their positions as illustrated, however, the motor 255 is energized for reverse rotation. The resultant reduction in frequency of the alternator 162 reduces the power in lines 23 and 24 and the wattmeter 500 immediately responds to move contact arm 501 to open the circuit of relay coil 516. Accordingly, the resistor 513 is effectively inserted in the motor circuit to slow down the motor and to produce a slower speed of operation in reducing the frequency than occurred in its operation to increase the frequency.

The system responds to develop maximum power output. The power is increased by the rising frequency and the vane 504 is moved in a clockwise direction by contact 501a but is not moved in the counterclockwise direction until after the opening of the circuit and not until contact member 501 engages the bumper 502.

The graphs 520 and 521 of Fig. 45, plotted with frequency as abscissae and respectively with power and timer cycles as ordinates, are helpful in understanding the operation of the control system. The graph 520 is exemplary of the relationship between power to the transducer 12 and frequency.

Plotted in arbitrary units with f_0 corresponding to the frequency at which maximum power is obtained, graph 521 illustrates the variations in frequency produced by the control system as it adjusts the frequency of the alternator for generation of maximum power. It has been assumed that the frequency f_1 is about 7½ percent below the frequency f_0 for maximum power. The graph 521 illustrates operation with resistor 513 having a value such that the motor speed will be doubled when it is removed from the motor circuit.

It is seen from graph 521 that about six timer cycles are required for the system to adjust the alternator 162 for the development of maximum power. More particularly it is observed that the motor 255, when operating to adjust the frequency as indicated by the

segments 521a, 521b, etc., increases the frequency to a greater extent than opposite rotation of the motor decreases the frequency. The latter is illustrated by the segments 521' and 521'', etc. For the case where the frequency is too high, the system functions to reduce it. The graph would be a mirror-image of graph 521 located to the right of the broken line drawn at f_0 .

The contact 503 and the bumper 502 may be adjusted on the vane 504 to vary their separation distances. Ordinarily such adjustment is made only when the system is first placed into operation to provide the sensitivity needed for stable control of a particular installation. The graph 521 is to be considered only as exemplary of the operation of one system, since with different contact positions the adjustments of generator frequency in increasing and decreasing directions may vary substantially from those shown. The number of timer cycles required for the system to reach equilibrium may in some cases be less than the six which have been illustrated and in other cases may be more.

Transmission lines

Again referring to Fig. 2, it will be recalled that mention was made that a feature of the present invention was the relatively open passage 13 through the central portion of the transducer for flow of mud and also the fact that such an unobstructed flow passage could and does extend throughout the length of drill pipe. Such a construction will be later described and may be the preferred construction. Obviously, however, if adequate space be retained in the drill pipe, in the drill collar and in the filter for flow of mud, a conductor assembly may be located within the passage through them. Such an assembly has been used in practice and is illustrated in Figs. 46-48. Novel features of the transmission lines disclosed herein are claimed in a copending application for U. S. Letters Patent of Henry E. Hull and Paul G. Berry, Serial No. 350,679, Patent No. 2,795,395.

As shown in Fig. 46, the conductors 23 and 24 from the transducer are brazed or soldered to inner and outer cylindrical conductors 401 and 402. The inner conductor 401 may be either solid or tubular, while the outer tubular conductor 402 is preferably cylindrical. Insulation which is and must be present between the conductors, and preferably between the conductors and the chevron seals 407 and 408, has been omitted in Fig. 48 in the interest of clarity.

In the vicinity where adjacent drill-pipe sections are fastened together, provisions are made for the separation of one section of transmission line from another. To this end, a conductor coupling member 405, illustrated in perspective in Fig. 47, connects the lower inner conductor 401 with the corresponding upper inner conductor 401a extending upwardly of the drill string. By providing slots 405a spring fingers are formed which, upon assembly of the transmission line, insures a low-resistance joint by their wiping action. Similarly, an outer conductor-connecting member 406 may be provided with similar spring fingers at opposite ends for wiping action with the lower outer conductor 402 and the upper outer conductor 403a.

All of the open space appearing in Figs. 46 and 47 within sheath 410 is filled with suitable insulating material and the severable joints between sheaths 409 and 410 and between sheaths 410 and 411 are made watertight by the provision of the sealing members 407 and 408. These sealing members are preferably of the chevron type provided with a series of flexible annular sealing members formed by a series of circumferential slots 407a and 408a. Thus, hydraulic pressure, from the mud or other liquid in the drill hole, is applied by way of each joint between casings to the slots 407a to expand the packing and to press the sealing members against their adjacent sheaths, increasing the tightness of the seal. The chevron seal 408 functions in like manner.

The manner in which the parts cooperate can be readily understood by referring to Fig. 48 in which the cylindrical conductor 406 is shown encircling electrical insulation 406a interposed between outer conductor 406 and the inner cylindrical conductor 405, insulation 406b being interposed between conductor 406 and the sheath 410. Suitable insulating material filling the open spaces within sheath 410 will be of resilient material and by configuration and surface bonding to the metallic elements 410, 406, and 405, will cause the bridging assembly to act as a unit.

To uncouple adjacent sections of the transmission line, with their respective sections of drill pipe 21n, shown fractionally in Fig. 46, the threaded connection of the drill string is unscrewed. The upper casing 411 is moved upwardly with the upper chevron seal 408. The upward force exerted on sheath 410 by the chevron seal 408, on the conductor 406 by conductor 403a, and on conductor 405 by conductor 401a may cause the bridging assembly to move upwardly with the upper section of drill pipe until the transmission line is separated. If the frictional forces between the bridging assembly and the lower section of transmission line are greater than those between the bridging assembly and the upper section of transmission line, the separation of the transmission line will also be accomplished but the bridging assembly will remain with the lower section 405, 406 of transmission line.

In assembling the line, the bridging assembly again acts as a unitary assembly. That assembly 450 may be placed on a terminal end of a section of the transmission line. As the upper slotted end of conductor 406 engages cylindrical conductor 403a, the slotted end of conductor 405 engages conductor 401a. While the assembly is normally placed upon the lower conductors, such as conductors 401 and 402, of Fig. 48, the connector assembly may be first placed on either end of a section of drill string with the other section then movable into circuit-completing positions by screwing together the drill-pipe sections to complete the assembly, with a substantial annular flow passage between the transmission line and the drill pipe.

To maintain the transmission line in substantially concentric disposition within the drill pipe, fins may be provided, perhaps two to a section of drill pipe, one centering arrangement 412 being shown in Fig. 48 and having three radial arms or fins 412b, two of them appearing in the drawing.

An understanding of a different type of transmission line will be facilitated by referring to the perspective view of Fig. 49, where conductors 23 and 24 are shown connected, as by soldering, to semi-annular conductors 421 and 422. The latter are in turn connected, as by silver soldering, to semi-annular conductors 423 and 424, the conductor 423 extending upwardly beyond the upper end of the conductor 424. Conductors 423 and 424 are disposed at substantially differing radial distances from the center line of the transmission line assembly. Corresponding downwardly extending conductors 421a-424a are respectively connected to conductors 421-424 by way of continuous annular bridging conductors 425 and 426 respectively of differing diameter. Opposite ends of the annular bridging conductor 426 have spring fingers (not shown in Fig. 49) which engage semi-annular conductors 424 and 424a. The opposite ends of member 426 may be slotted in the manner above described to form the spring fingers and to assure a good wiping contact. Similarly the opposite ends of annular bridging conductor 425 (which are preferably slotted) engage the adjacent ends of conductors 423 and 423a. By reason of the selected differing diameters, the coaxial annular bridging conductors 425 and 426, respectively connect conductors 423-423a and 424-424a regardless of their relative angular positions about the longitudinal axis. Accordingly, it is unimportant to have one semi-annular section of

transmission line in circumferential alignment with any other. As each section is brought into engagement with the next section, the annular bridging conductors 425 and 426 establish low-resistance power connections.

As shown in the sectional view of Fig. 51, in which the insulation is again omitted for purposes of clarity, a connecting member 430 is threaded secured in permanent connection, as by welding at 431a, to the upper end of a lower section of drill pipe 431 to form a box end which threaded and removably receives the connecting member 432; a good grade of packing material 433 is preferably included to minimize air space in the region of the connector. An inner lining member 434 extends upwardly from the lower section of drill pipe 431 and terminates in the region in which there is located a chevron-type seal 435. A short lining member 436 extends from the lower joint at seal 435 to an upper joint at a second chevron seal 437. The lining member 438 from the upper section of the drill pipe terminates at the location of the chevron seal 437. The liners 434, 436, and 438 are coaxial with the longitudinal axis of the drill pipe and provide an open and unobstructed passage for flow of mud to the drill bit.

In Fig. 52, the electrical interconnection between the semi-annular conductors 421a and 423a clearly appears, as does the similar connection between conductors 422a and 424a. In the region immediately below the chevron seal 437, as shown in Fig. 53, it will be seen that the annular bridging conductor 426 is in electrical contact with the semi-annular conductor 424a but is spaced inwardly a substantial distance from the semi-annular conductor 423a. In the region adjacent the end of annular bridging conductor 426, it will be seen from Fig. 54 that the bridging conductor 426 is spaced inwardly from the bridging conductor 425, while the latter is in good electrical engagement with semi-annular conductor 423. Similarly, Fig. 55 illustrates the electrical connection between bridging conductor 426 and the semi-annular conductor 424. From Figs. 53 and 55, it is clear that the upper section may be in any angular position relative to the angular position of the lower section of drill pipe. Change in such relative angular positions would only have the effect of positioning the semi-annular conductors about the circumferences of their respective annular bridging conductors.

The manner in which the parts may be assembled and disassembled will be clearly understood with reference to Figs. 56 and 57. The semi-annular conductors 423 and 424 embedded in insulation in the lower section of drill pipe (not shown), project upwardly to different levels to receive the bridging conductors 425 and 426. The bridging conductor 426 is disposed for elastic sliding engagement with the inner surface of conductor 424 and the bridging conductor 425 makes like engagement with the inner surface of conductor 423. After placement of the assembly 450 in the manner described, the adjacent length of drill string is then moved downwardly to move the inner surface of conductor 423a over and along the upper end portion of conductor 425 and to move the inner surface of conductor 424a over and along the upper end portion of conductor 426. The electrical connections are then complete and they may be broken upon disassembly of the drill string by reversal of the foregoing steps.

It will be apparent that a desired polarity can be predetermined and maintained throughout the electrical transmission system of Figs. 49-57 if the conductors in each section of the drill string are constructed as illustrated schematically in Fig. 58, because the same electrical continuity is always present between the corresponding conductor of one conducting section and the corresponding conductor of the next conducting section. The substantially semi-annular conductor 423a of the upper conducting section shown in Figs. 49-58 corresponds to the substantially semi-annular conductor 423 in the lower conducting section, since each of conduct-

tors 423 and 423a is identical in spacing from the axis and each always contacts the outer annular bridging conductor 425. The substantially semi-annular conductor 424a of the upper conducting section similarly corresponds to the substantially semi-annular conductor 424 of the lower conducting section. Since each of these two conductors is identical in spacing, they always contact the inner annular bridging conductor 426. Although the polarity feature is not necessary in the transmission of A. C. power, it is a very convenient feature where D. C. power is to be transmitted, since it obviates the use of trial and error in connecting D. C. power with a predetermined polarity to a load.

More specifically, Fig. 58 shows the transmission line extending between three lengths of drill pipe. The upper length of drill pipe may terminate, as shown in Fig. 46, in a tapered, threaded end within which there will be semi-annular conductors 423a and 424b respectively silver-soldered to semi-annular conductors 421a and 422a. With the connector assembly in place and the line assembled, current will flow through a path including conductors 421a, 423a, coupling conductor 425, conductors 423, 421b, 423b, coupling conductor 425a, conductor 423c, and by conductor 421c to the next adjacent length of drill pipe. The current flow will always be as traced, since it will not matter in what annular position the drill pipe may be when it is assembled as a part of the drill string. The return path which may be similarly traced will likewise always be the same.

Fig. 59 is identical with Fig. 58 except that, instead of the longer semi-annular conductors 423 and 423b being soldered to the same conductor, they are in Fig. 59 silver-soldered to different semi-annular conductors 421b and 422b of a drill pipe section, the same transposition occurring with respect to the shorter semi-annular conductors 424 and 424b. Accordingly, the current, flowing by way of conductor 421b and the shorter semi-annular conductors 424d of decreased radius, slidably engages the bridging sleeve 426a and thence flows by way of semi-annular conductor 424c and 422c. Thus, in the lower tool-joint region, identified by the arrows, there is transition of the current from conductor 421b to conductor 422c. By including a number of lengths of drill pipe of the kind illustrated in Fig. 59 at spaced intervals along the drill string, there will be transposition of current flow at each such length of drill pipe, and accordingly the line capacitance with respect to ground may be balanced out.

The protecting sheaths or liners 434, 436, and 438, Fig. 57, define a large open passage. During the usual drilling operation, this passage provides a path for the flow of mud fluid down the drill string, and during other operations this passage provides space for the insertion of tools used in surveying, testing, and fishing operations. The inner diameter of the protecting sleeve 436 is limited, of course, by the fact that the two concentric annular bridging conductors 425 and 426 and the three concentric annular layers of insulation are present between sleeve 436 and the drill pipe. Since each conducting section of a length of drill pipe can be made to comprise only one annular layer in which each of the substantially semi-annular conductors 421a-424a is located, and only two annular layers of insulation, the diameters of the protecting liners 434 and 438 may be somewhat larger than the diameter of the protecting liner 436. The end portion of the protecting liner 438 in the upper conducting section and the end portion of the protecting liner 434 in the lower conducting section have diameters equal to that of the protecting liner 436 of the bridging assembly. These three diameters are made equal to provide a smooth wall in the inner passage at each sealing or junction point.

Although the chevron-type seals 435 and 437, as shown in Fig. 51, are preferred, other sealing means could be substituted. O ring seals, compression seals, or other

suitable seals could be used in place of the chevron-type seals. It is necessary to provide suitable sealing means at every junction between conducting section and annular connector, in order to prevent the leakage of mud fluid or other foreign matter into the conducting and insulating members. Such leakage would, of course, damage the electrical power transmission system.

Since all the contacts between the conducting sections and the annular connectors are overlapping contacts rather than abutting contacts, close tolerances are not required in the longitudinal dimensions of the annular connectors. The dimensions of the annular connectors are preferably chosen so as to provide small annular spaces in each junction. Thus, fairly large tolerances are permissible, and provision for tool-joint wear is made. The regions on the annular connectors near these variable spaces should preferably be covered with an insulating grease before insertion of the connectors into the drill pipe. The electrical transmission system can be checked progressively by connecting a continuity tester, or other suitable test equipment, to the section of drill pipe just added to the drill string through a plug-in unit similar to the annular bridging sleeve connector. Continuity tests may then be made during the drill-string lowering operation.

In disassembling the drill string, each annular bridging sleeve connector should be removed from its section of drill pipe to eliminate any pockets in which mud or other foreign matter might collect. It is apparent from Figs. 51 and 57 that, if the upper section of drill pipe were disconnected from the lower section of drill pipe and the annular bridging sleeve connector left connected to the lower conducting section, an annular pocket would be present between the upper portion of the annular bridging sleeve connector and the box end of the drill-pipe section. Foreign matter could collect in this pocket and cause damage to the electrical parts. This is one reason why the annular bridging assembly 450 is preferably made as a separate removable unit, as shown in Fig. 56, rather than as the terminal portion at one end of a conducting section. It would not be desirable to provide the annular bridging sleeve connector 450 as an integral terminal portion of the upper conducting section, because if this were done the electrical terminals would protrude beyond the pin end of the upper drill-pipe section, and when this drill-pipe section is disconnected from the lower drill-pipe section 431, the protruding parts would be subject to damage during normal handling.

A further modification of the transmission line is shown in the perspective view of Fig. 60 and the sectional view of Fig. 61. It will be recalled that in the semi-annular line of Fig. 56, the semi-annular terminal conductors 423 and 424 (and 424a and 423a) have different radii. Accordingly, as shown in Fig. 60, semi-annular conductors 421, 421a, 422 and 422a may have annular or cylindrical end portions 423c, 423d, 424c, and 424d. Thus, a greater contact area is provided for the bridging conductors 425 and 426. Also of importance is the fact that as shown in Fig. 61, the transmission line is stronger at its end portions where it is likely to receive greater abuse in handling.

In Fig. 61, additional features appear. The inner lining or sheath 434 is made thicker throughout its length except in the region of the chevron seals 435 and 437. The seals themselves are provided with metallic backing members 435a and 437a to provide additional strength and to provide annular pockets in which said seals 435 and 437 may nest. Annular corner reinforcing members 440 and 441, which are also provided, may consist of a fine-mesh screen embedded into the chevron seal during molding thereof, as best shown in Fig. 62.

In accordance with the disclosure as a whole, it will be seen that the present invention involves transducers of a new and radically different type. The transducer must not interfere with the circulation of the drilling fluid or mud and the high-level vibration of the transducer and the

bit must not disturb the electrical connections through which both direct and alternating currents are delivered to the transducer.

In the transducer itself, the outer member forming the return path for the magnetic flux has a permeability and working flux density at least as great as that of the inner member made of magnetostrictive material. Thus, the outer member may either be of magnetostrictive material as in Figs. 2 and 13 or it may be of different material of high permeability and high working flux density as in Fig. 14, the cross-sectional areas of the two members being related inversely as their maximum working flux densities. Where the outer member has the high permeability and high working flux density—much greater than those of the magnetostrictive material—its cross-sectional area may be smaller and thus its area is inversely related to the ratio of the maximum working flux densities. The total flux in the two members would be approximately the same. Lack of protuberances and the smooth contour from one end of the transducer to the other avoids any possibility of coupling between the vibrating transducer or column and the drilling fluid. Considering the fact that the transducer operates in a viscous medium, protuberances extending into the drilling fluid or mud would produce a high damping action and there would result considerable loss of energy which is minimized in accordance with the present invention by the uniform cross-sectional area extending from the region of the bit into at least a part of the filter. In a preferred modification, the filter itself may be made of the same cross-sectional area as the transducer further to avoid a changing cross-sectional area which might give rise to undesirable loss of vibratory energy. The transducer itself is composed of solid materials, the insulation and seals preventing either the existence in the transducer or the entry into it of gaseous or liquid materials. The only gaseous or liquid materials present in the transducer will be the minute quantities present in solution in the solid materials. The transducer winding is designed to provide, for the maximum allowable current density in the winding, an exciting field of an intensity at which the product of the driving mechanical stress due to magnetostriction and the cross-sectional area of the transducer core is a maximum. The maximum allowable current density in the winding will be determined primarily by the wire resistance, coil geometry, and allowable temperature rise above ambient in the wire and coil insulation. A secondary factor is the choice of the maximum percentage of input power to be dissipated in the exciting coil. Typical maximum allowable current densities lie in the range of 1000-2000 amperes per square inch. The optimum exciting field is found graphically from the product of the mechanical stress and core cross section as functions of exciting field. The change in the magnetic field in the magnetostrictive members produces the driving force or stress and that is also dependent upon the cross-sectional area of the magnetostrictive transducer core. It has been found that greatest efficiency can be attained when the aforesaid product is made a maximum. Thus, the space occupied by the coil may be made a minimum by properly relating the copper size and the number of turns. More specifically, with the space occupied by the coil determined, the product of the current and the number of conductors results in a figure representative of the current in the space or area occupied by the coil. If the current in the area then be divided by the area itself, the maximum allowable current density, above referred to, will be known. It is this current density which is made maximum for a particular winding.

It will be understood, of course, that, while the forms of the invention herein shown and described constitute preferred embodiments of the invention, it is not intended herein to illustrate all of the possible equivalent forms or ramifications of the invention. It will also be understood that the words used are words of description rather than

of limitation, and that various changes, such as changes in shape, relative size, and arrangement of parts, may be substituted without departing from the spirit or scope of the invention herein disclosed.

5. What is claimed is:

1. A well-drilling system comprising a drill string, a vibratory column including a magnetostrictive transducer at the lower end of said drill string having a drill bit secured to the lower end thereof, said transducer including an elongated member of magnetostrictive material, the cross-sectional area of which is a substantial proportion of the cross-sectional area of the hole provided by said drill bit and substantially uniform throughout its length and of adequate strength for transmission of substantial torque, an energizing winding for said magnetostrictive member, means for energizing said winding to produce a changing flux of high peak density within said magnetostrictive member to vibrate said bit, said drill string including means for applying a static load to said elongated member and to said bit in a direction to press it against strata to be penetrated, a filter formed of torque-transmitting members interposed between and connected to said vibratory column at the lower end of said drill string for isolating the upper portion of said drill string from vibrations produced in said column while transmitting said static load and said torque to said bit, said filter members being about one-quarter wave length long at the resonant frequency of said column, the first section of said filter above said column having a mechanical impedance less than that of said column by a factor of at least 2.5 and the second section of said filter having a mechanical impedance greater than that of said first section by a factor of at least 2.5, said mechanical impedance being defined as the product of the mass per unit length and the velocity of propagation of longitudinal waves, said filter including a plurality of sections differing one from the other as said first and said second sections differ from each other and from said column, and means for controlling the excitation of said winding for exciting said transducer at the resonant frequency of said column while in engagement with strata to be penetrated to move said bit into and out of impact engagement with said strata during application thereto of said torque and of said static load.

2. A well-drilling system comprising a drill string having a mud passage extending lengthwise thereof, a vibratory transducer including a cylindrical housing secured to the lower end of said drill string, said vibratory transducer extending lengthwise of said housing and at one end secured to the lower end of said drill string and including an extension of said mud passage, a drill bit connected to the lower end of said transducer and having a mud passage therethrough, said transducer between said bit and said drill string including nesting, concentric, elongated, cylindrical, vibratory members of magnetostrictive material, an energizing winding having its turns distributed between and along said cylindrical magnetostrictive members, said members being closely spaced in the regions beyond the ends of said winding to form low reluctance paths for magnetic flux, and said members being welded together in regions spaced outwardly from the ends of said winding beyond said low reluctance paths, the cross-sectional area of said transducer being a substantial proportion of the cross-sectional area of the hole provided by said drill bit and substantially uniform throughout its length, and means in said drill string for applying at least a part of the weight of said drill string to said transducer and to said bit in a direction to press it with a predetermined static force downwardly against strata to be penetrated.

3. The combination set forth in claim 2 in which said magnetostrictive members each comprise a plurality of laminations disposed in approximate radial array about a center and at least some of which are of variable thickness in approximate radial directions of the transducer and

electrically insulated one from the other except where welded together to form a rigid cylindrical active member of said transducer.

4. The combination set forth in claim 2 in which said drill string in the region immediately above said transducer comprises a filter including adjacent said transducer lengths of pipe alternately having masses differing from each other by a factor not less than 2.5 and lengths equal to each other and avoiding lengths close to an integral number (including zero), of half wave lengths at the resonant frequency of the transducer for reflecting back to said transducer upwardly moving vibratory energy.

5. A vibratory motor for reciprocating a bit comprising a plurality of long laminations disposed in circular array with each said lamination extending in a substantially radial direction and adhesively bonded together with an insulating bonding agent, a coil, a winding encircling said laminations and electrically insulated therefrom for producing magnetic flux lengthwise thereof, and additional laminations being similarly disposed and similarly bonded together and at their respective ends secured to the ends of the first-mentioned laminations to form a closed flux path.

6. The combination set forth in claim 5 in which the respective ends of said laminations are welded together in regions outwardly spaced from the adjacent ends of said winding.

7. The combination set forth in claim 5 in which said first-named laminations are provided with a circumferential recess to receive the turns of said winding.

8. The combination set forth in claim 5 in which the lengths of said laminations which extend outwardly from the respective ends of said windings are several times the width of said laminations to provide return flux paths of low reluctance, said laminations being welded together in regions beyond said low reluctance flux paths.

9. The combination set forth in claim 5 in which laminations adjacent said winding form slots extending lengthwise thereof, conductors disposed within said slots, and means connecting said conductors to said winding for energization thereof.

10. The combination set forth in claim 5 in which the laminations encircled by said winding and those forming said return flux path overlie each other and the assembly as a whole being bonded together.

11. A vibratory motor comprising two sets of laminations respectively disposed in circular array with each said lamination extending in a substantially radial direction to form two closely fitting co-axial members, one of the said members being recessed along the surface facing the other of said members, a winding having a plurality of turns within said recess for producing magnetic flux in both of said members, and the laminations of at least one of said members being made of magnetostrictive material and the laminations of said other member being made of material having a permeability and maximum working flux density at least as great as said magnetostrictive material.

12. A vibratory motor comprising two sets of laminations respectively disposed in annular array with each said lamination extending in a substantially radial direction to form two closely fitting co-axial members, the inner array having a flow channel extending axially thereof, one of the said members being circumferentially recessed along a region inwardly spaced from its end portions and along the surface facing the other of said members, a single-layer winding having a plurality of turns within said recess for producing magnetic flux in both of said members, and the laminations of at least one of said members being made of magnetostrictive material and the laminations of said other member being made of material having a permeability and maximum working flux density at least as great as said magnetostrictive material, the close-fitting end portions of said

members providing low reluctance flux paths to minimize the intensity of the magnetic field at the ends of said members.

13. A vibratory motor comprising two sets of laminations respectively disposed in circular array to form two closely fitting co-axial members, one of the said members being recessed along the surface facing the other of said members, a winding having a plurality of turns within said recess for producing magnetic flux in both of said members, and the laminations of at least one of said members being made of magnetostrictive materials and the laminations of said other member being made of material having a permeability and maximum working flux density at least as great as said magnetostrictive material, and the cross-sectional areas of said members being related inversely as their maximum working flux densities.

14. The combination set forth in claim 13 in which the length of said recess is materially less than the respective lengths of said members to provide beyond the respective ends of said coil flux paths of low reluctance between said members.

15. The combination set forth in claim 14 in which the respective ends of said members are secured together and to force transmitting members.

16. The combination set forth in claim 14 in which the magnetic field at the respective ends of said members is low by reason of said low reluctance paths, and having an unlaminated metallic stress-transmitting member rigidly secured to the respective ends of said members, the intensity of said magnetic field in the region of said members being insufficient to produce substantial heating thereof.

17. The combination set forth in claim 16 in which the wall thicknesses of said members comprise the wall thickness of the transducer, a protective sheath encircling the transducer, and the internal and external surfaces being smooth and without protuberances by reason of cross-sectional areas from inner surface to outer surface which throughout the length of said transducer are uniform.

18. The combination set forth in claim 13 in which corresponding edges of said laminations face inwardly toward the centrally located flow channel.

19. The combination set forth in claim 13 in which the entire transducer assembly is composed of solid materials to the exclusion of the existence in, or entry to, the assembly of gaseous or liquid materials except in the minute quantities present in solution in the solid materials.

20. The combination set forth in claim 13 in which the exciting winding is of such proportion as to provide, at the maximum allowable current density in said winding, an exciting field at which the product of the driving mechanical stress due to magnetostriction and the cross-sectional area of the magnetostrictive transducer core is a maximum.

21. Vibratory driving structure comprising laminations thin and long and disposed in annular array about a central axis with each said lamination extending in a substantially radial direction, said laminations being rigidly bonded together, a winding having a plurality of turns disposed in single layer along the length of said laminations from regions spaced inwardly from the respective ends thereof, said laminations being formed with magnetostrictive material having the property of elongating and contracting upon production by said winding of magnetic flux therethrough, a plurality of laminations long and thin and bonded together in annular array about said first-named laminations with each said lamination extending in a substantially radial direction, said outer annular array of laminations at least in the regions extending outwardly from the ends of said winding having only a small clearance from the inner annular array of lamination.

tions to minimize the spacing therebetween, the reluctance between the inner and outer arrays of laminations being low by reason of the substantial length of the contiguous areas, and said inner and outer arrays of laminations being welded together at their extreme ends and in regions spaced outwardly from said low reluctance paths whereby upon energization of said winding a magnetic field of low intensity is produced in the welded areas and which does not produce high temperature rises therein.

22. The combination set forth in claim 21 and in which the turns of said winding are adhesively secured both to said inner and outer annular arrays of laminations and in which there are provided inner and outer protective casings for said inner and outer annular arrays of laminations.

23. The combination set forth in claim 21 in which slots extend lengthwise of one of said annular arrays of laminations, supply conductors disposed in said slots, and means for electrically connecting said winding and said supply conductors for energization thereof.

24. The combination set forth in claim 21 in which channel means for reception of conductors extends lengthwise of one of said arrays of laminations.

25. A vibratory structure comprising laminations of magnetostrictive material disposed in circular array about a longitudinal axis, a cylindrical casing, the inner ends of the laminations abutting against the casing, a single-layer winding disposed about said laminations, the respective ends of the winding being spaced inwardly from the opposite ends of said laminations, a plurality of laminations distributed in circular array around said winding and disposed in close proximity to the inner array of laminations in the regions beyond the ends of said winding, the outer array of laminations being formed of a material of substantially higher permeability than said inner array and having widths, taken radially, less than those of said inner array but providing a flux path whose saturation flux is approximately the same as that of said inner array of laminations.

26. Vibratory structure comprising a first assembly of a plurality of elongated laminations bonded together with an electrically insulating bonding agent, at least outer portions of said assembly of laminations being arcuate, a second assembly of laminations like that of said first assembly, a winding disposed about each assembly of laminations, electrical connections interconnecting said windings for production of magnetic flux in one group of laminations in a direction cumulative with the flux produced by the other winding in the other group of laminations, and a housing of arcuate shape against which the arcuate surface of said groups of laminations abut, there being an open and unobstructed space forming a fluid passage extending lengthwise of said groups of laminations and inside said housing.

27. The combination set forth in claim 26 in which fluid passages are disposed on opposite sides of said groups of laminations.

28. The combination set forth in claim 26 in which said groups of laminations are disposed in spaced relation with said casing, said fluid passage being annular in shape and extending between the outer surfaces of said laminations and the inner surface of said casing.

29. The combination set forth in claim 26 in which said passage extends lengthwise of said casing through the central portion thereof.

30. The combination set forth in claim 26 in which there are a plurality of groups of laminations each having a winding, each pair of them being disposed adjacent outer portions of the casing and leaving at the central portion of the casing a flow passage rectangular in shape.

31. Vibratory driving structure comprising laminations thin and long and disposed in annular array about a central axis, said laminations being rigidly bonded together, a winding having a plurality of turns disposed in

single layer along the length of said laminations from regions spaced inwardly from the respective ends thereof, said laminations being formed with magnetostrictive material having the property of elongating and contracting upon production by said winding of magnetic flux therethrough, a plurality of laminations long and thin and bonded together in annular array about said first-named laminations, said outer annular array of laminations at least in the regions extending outwardly from the ends of said winding having only a small clearance from the inner annular array of laminations to minimize the spacing therebetween, the reluctance between the inner and outer arrays of laminations being low by reason of the substantial length of the contiguous areas, and said inner and outer arrays of laminations being welded together at their extreme ends and in regions spaced outwardly from said low reluctance paths whereby upon energization of said winding a magnetic field of low intensity is produced in the welded areas and which does not produce high temperature rises therein; the laminations of at least one annular array thereof being wedge shaped, with the angles of the respective wedges being selected relative to thickness so that together each such array of laminations forms an annulus of thickness equal to the width of the laminations.

32. Vibratory driving structure comprising laminations thin and long and disposed in annular array about a central axis, said laminations being rigidly bonded together, a winding having a plurality of turns disposed in single layer along the length of said laminations from regions spaced inwardly from the respective ends thereof, said laminations being formed with magnetostrictive material having the property of elongating and contracting upon production by said winding of magnetic flux therethrough, a plurality of laminations long and thin and bonded together in annular array about said first-named laminations, said outer annular array of laminations at least in the regions extending outwardly from the ends of said winding having only a small clearance from the inner annular array of laminations to minimize the spacing therebetween, the reluctance between the inner and outer arrays of laminations being low by reason of the substantial length of the contiguous areas, and said inner and outer arrays of laminations being welded together at their extreme ends and in regions spaced outwardly from said low reluctance paths whereby upon energization of said winding a magnetic field of low intensity is produced in the welded areas and which does not produce high temperature rises therein; the laminations in both the inner and outer arrays being wedge shaped.

33. Vibratory driving structure comprising laminations thin and long and disposed in annular array about a central axis, said laminations being rigidly bonded together, a winding having a plurality of turns disposed in single layer along the length of said laminations from regions spaced inwardly from the respective ends thereof, said laminations being formed with magnetostrictive material having the property of elongating and contracting upon production by said winding of magnetic flux therethrough, a plurality of laminations long and thin and bonded together in annular array about said first-named laminations, said outer annular array of laminations at least in the regions extending outwardly from the ends of said winding having only a small clearance from the inner annular array of laminations to minimize the spacing therebetween, the reluctance between the inner and outer arrays of laminations being low by reason of the substantial length of the contiguous areas, and said inner and outer arrays of laminations being welded together at their extreme ends and in regions spaced outwardly from said low reluctance paths whereby upon energization of said winding a magnetic field of low intensity is produced in the welded areas and which does not produce high temperature rises therein; and threaded coupling mem-

bers respectively joined by welding to the welded ends of said laminations.

34. The combination set forth in claim 33 in which a bit is rigidly secured to one of said coupling members and the lower end of the drill string is secured to the other of said coupling members, said outer array of laminations and the lower end of said drill string being surrounded by a protective casing, and conductors extending adjacent the inner surface of said casing and respectively connected to said winding for energization thereof.

35. A well-drilling system comprising a drill string having a mud passage extending lengthwise thereof, a vibratory transducer secured to the lower end of said drill string and including an extension of said mud passage, a drill bit connected to the lower end of said transducer and having a mud passage therethrough, said transducer between said bit and said drill string including an elongated vibratory member, means uniformly distributed along said member for vibrating it, the cross-sectional area of said transducer being substantially uniform throughout its length, and means including weight of said drill string for applying static force to said bit in a direction to press it against strata to be penetrated, said drill string in the region immediately above said transducer comprising a plurality of sections of like material and, starting at the top of the transducer, alternately having first a materially reduced and then a materially increased wall thickness, compared each with the other, and each such section having a length about one-quarter of a wave length at the resonant frequency of the transducer, these sections forming a filter to prevent appreciable net flow of vibratory energy in an upward direction from the top of the transducer.

36. In a well-drilling system including a drill bit and a rotatable torque-transmitting drill string with a mud passage extending lengthwise thereof for flow of drilling mud therethrough, the combination of a transducer of the magnetostrictive type comprising a rigid torque-transmitting assembly of thin laminations of magnetostrictive material of substantial length and electrically insulated one from the other, an energizing coil spirally wound about and distributed along said assembly intermediate the respective end-portions of said laminations, the respective end-portions of said laminations in regions spaced from

the adjacent ends of said coil being welded together, means including said welded end-portions for rigidly securing one end of said rigid assembly to said drill string and for securing the opposite end of said assembly to said drill bit, said transducer and said drill bit having mud passages for flow therethrough of said drilling mud, said assembly of said laminations being disposed in a position relative to the transducer mud passage so that the edge-portions of said laminations face said mud passage for dissipation to the drilling mud of heat flowing outwardly from each lamination toward said last-mentioned mud passage, the cross-sectional area of said rigid assembly of magnetostrictive material being uniform lengthwise of said assembly and comprising a substantial proportion of the cross-sectional area of the drill hole provided by said drill bit, means for energizing said winding to produce reciprocation of said transducer and of said bit, and a filter formed of torque-transmitting members disposed between said transducer and said drill string.

20 37. The combination set forth in claim 36 in which the length of said transducer is equal to an integral multiple including unity of one-half a wave length for an operating frequency selected between about 100 cycles per second and about 1,000 cycles per second and corresponding with approximate mechanical resonance of said transducer.

25 38. The combination set forth in claim 36 in which said laminations of said assembly are disposed in approximate radial array about a center and at least some of which are of variable thickness in approximate radial directions 30 of the transducer to form a rigid cylindrical member.
